UNITED STATES PATENT OFFICE

133,368

DESIGN FOR A COMBINED FLOWERPOT AND HOLDER THEREFOR

Frank A. Cardelli, Chicago, Ill.

Application May 30, 1942, Serial No. 107,057

Term of patent 3½ years

To all whom it may concern:

Be it known that I, Frank A. Cardelli, a citizen of the United States of America, residing at 1828 W. Hubbard Street, in the city of Chicago, in the county of Cook and State of Illinois, have invented a new, original, and ornamental Design for a Combined Flowerpot and Holder Therefor, of which the following is a specification, reference being had to the accompanying drawing, forming a part thereof.

Fig. 1 is a top plan view of a combined flower-pot and holder therefor, showing my new design; and

Fig. 2 is an elevational view thereof, partly in section.

The characterizing features of my design reside in the portions shown in full lines in the drawing.

I claim:

The ornamental design for a combined flowerpot and holder therefor, substantially as shown and described.

FRANK A. CARDELLI.
